UNITED STATES PATENT OFFICE.

LEWELLEN A. ELY, OF DAYTON, OHIO.

PLAYING-CARDS.

1,076,492.

Specification of Letters Patent.

Patented Oct. 21, 1913.

Application filed March 4, 1910. Serial No. 547,285.

To all whom it may concern:

Be it known that I, LEWELLEN A. ELY, a citizen of the United States, residing at Dayton, in the county of Montgomery and State of Ohio, have invented new and useful Improvements in Playing-Cards, of which the following is a specification.

The invention relates to an improved game including a pack of cards which are particularly designed for playing in a manner similar to the usual card game, the game of foot ball.

The cards forming the essential of the improved game are designed particularly with a view to permitting practically all of the plays possible in the usual game of football while at the same time combining with such plays the option or selection usually permitted a player in a card game. This provides an exceedingly interesting and highly instructive variation which permits skill and knowledge of one pair of players to overcome better cards in the hands of players of less knowledge of the game of football and old line cards.

In the accompanying drawings, I have illustrated in Figures 1 to 12 inclusive the entire cards of one suit of a pack. In Figs. 13, 14 and 15 are illustrated the cards of the remaining suits corresponding to the cards of the main suit illustrated, shown in Fig. 4, it being understood that each of the three suits denoted by the cards in Figs. 13, 14 and 15, will have the same number of cards as in the suit fully illustrated, and differing from the cards of said illustrated suit only in that they bear their own suit characteristic. Fig. 16 illustrates an additional card, which may be termed "accidental" dent."

In making up the pack, which it will thus be seen contains forty-nine cards, they are divided into four suits, distinctively illustrated in Figs. 1, 13, 14 and 15. The suit of cards illustrated in Fig. 1 will be termed the "gridiron", the suit illustrated in Fig. 13 will be termed the "grandstand", the suit illustrated in Fig. 14 will be termed the "ball" and the suit illustrated in Fig. 15 will be termed the "goal". The gridiron and grandstand suits are preferably colored red while the ball and goal suits are colored black, though it is to be understood that any contrasting colors desired may be used.

Ten cards of each suit have a fixed play-

ing value under all conditions, which cards are illustrated in Figs. 3 to 12 inclusive, and may be designated as follows: The lowest card, that shown in Fig. 3, is termed "center" and has a playing value of two; the next, shown in Fig. 4, is termed "left guard" and has a playing value of three; the next, that shown in Fig. 5, is termed "right guard" and has a playing value of four; the next, that shown in Fig. 6, is termed "left tackle" and has the playing value of five; the next, that shown in Fig. 7, is termed "right tackle" and has a playing value of six; the next, that shown in Fig. 8, is termed "left end" and has a playing value of seven; the next, that shown in Fig. 9, is termed "right end" and has a playing value of eight; the next, that shown in Fig. 10, is termed "quarterback" and has a playing value of nine; the next shown in Fig. 11, is termed "left halfback" and has a playing value of eleven; while the card shown in Fig. 12 is termed "right halfback" and has the playing value of twelve.

In addition to the cards enumerated, there are included in each suit two additional cards the first of which is illustrated in Fig. 1 and is called "foul" or "kicker", having the playing value of ten. This card in each suit constitutes what may be termed the "bower" of the familiar game of euchre, and the particular "kicker" card of the trump suit is the high playing value card (except the accident), while the "kicker" card of the corresponding color suit to the trump may be termed the "left bower" and second in playing value to the "right bower". Each suit also contains a card having the playing value of the card illustrated in Fig. 2, which card is termed the "fullback" or "lonesome", and has a playing value of one or thirteen, in accordance with the play. The deck also includes one card which may be termed the "accident", which card is illustrated in Fig. 16, and in use, except in the specific instances hereinafter noted, is high playing value card.

Attacks are dealer and partner, at start of each half, and hold the ball. Defense are two opposing players, guarding "goal", the fifty-five yard line. The attacks always are the couple that have possession of the ball. Kicks is the term used instead of "tricks", "strikes", or "books", etc. Scrimmage is term used instead of "shuffling" as in other games. Trump is the card turned after the

first deal, in each series of plays, until goal is reached. This trump card is turned next after dealing the designated number of cards to each player, and rules until goal is made 5 by one side, unless the half ends sooner, and any card of this trump suit, is of higher value than any other card of off suit. If accident, turn "trump" that may designate "no trump" or it may and should be scrimmaged lower into deck, and another card turned for trump. Accident is always high trump, unless "killed" in a "run" or "straight."

Deal should be by players in turn, commencing each scrimmage with the player dealing, who is to play first, if ball is at center. During play of game, if it becomes necessary to re-scrimmage all the cards, then anyone may deal, but first play is from the 20 party in possession of ball, whose card took last kick.

Lead is by dealer, one of the attacks at start of game. After beginning play and until count is made that player leads who took last kick if taken by side in possession of the ball, but if kick is taken by either of the defense, then the lead is from player to the left of previous leader. The "loss of the ball" carries with it privilege of "lead."

30 Straight flush (counts only on downs), consists of four cards, same suit running in straight consecutive sequence or kick taking value, the accident being high trump or plays at its special privileges. A straight run is any four consecutive value cards (accident as any card). A flush consists of four cards same suit. (Left kicker belongs to trump suit). Straight tackle is when same color and value is played. Off side 40 tackle is when same value is played, but of opposite color. Tackle below is for one of the defense to take a kick with a trump of less sequence value than the card led by the side in possession of the ball. Forward pass 45 consists of the lead of any low "2", which calls out a still higher card at second hand, and, if successful, kick goes to partner.

Half time for a regular game shall be thirty-five minutes, and stop instantly as the 50 time expires for each half. Two halves for full game make seventy minutes, and the ball is in the possession of the respective sides successively at the start of the different halves. Lost time shall not be made up for any reason whatever. Set alarm at thirty-five minutes after starting play, then stop as alarm sounds.

Rules for playing.

60 1. Deal to each of four players (one card at a time) four cards, after thorough scrimmage. First deal and lead is for one of attacking side. Turn next card face up, centrally on table for trump, where it remains 65 in plain view until a count is made. If the

accident turns as trump, it should be shuffled lower into deck, after which the next card is turned for trump. After the four cards are played, deal four others as before, and still again the remaining four cards to each, unless goal has been previously reached. If neither side has reached the fifty-five yard line of their opponents, then re-scrimmage all the cards except the trump and 70 deal around again, and again until goal is reached for count, then begin at center again, the side in possession of ball leading, the last one of them to have taken kick, or if last kick was taken by a defense, then the attack seated at left of player who took kick. 75

2. Play starts with pin or peg at center on side of party having possession of ball, this pin being moved forward or back, and across board as plays are made according to rules, that demand it.

3. Game is won by side that scores most counts during time of playing game.

4. Points are "touchdown" 5. "Field goal" 4. "Touch back" 3. "Safety" 2. "Kicked goal" 1. Touch down is when pin or ball reaches the opponent's fifty-five yard line. Field goal is when a straight or flush (thirty yards gain) reaches fifty-five yards. Touch back is for defense, at kickoff, to carry back ball to fifty-five yard line. Safety is when attacks lose the ball back of their fifty yard line. Kick for goal is made when side securing touch down gets next kick. This being after fresh scrimmage, a card is drawn by each player.

5. First play is the "kick off", this recurring first lead of each deal of four cards. Gain or loss on kick off is represented by deducting total of corner points (card values) of one side from the sum total of 105 points of opponents, and when attacks secure the kick, it is an advance, but if defense take kick, it scores loss. Move score pin.

Rule 5^a: Player of "accident" is penalized twenty yards unless it was unavoidable, i. e., was called for by a trump lead.

6. Downs are the three kicks following any kick off, lead being always with side in possession of the ball, and the attacks must take two of these or lose the ball. If they secure three kicks after the kick off it scores fifteen yards gain. Two kicks score ten yards gain, and the last kick five yards only for side in possession of ball. The ten 115 yard gain is not scored until two kicks are secured while ball is in possession of one side.

7. Gains on downs: A straight flush, fifty-five yards gain to side taking kick, and if it reaches goal line (55) is a "touch down", scores five points. 4—11—44 in any trick is touch down from any point of field for attacks. A flush of four cards is field goal if the thirty yards advance reaches 130

- goal. A run of four cards (a straight) is same as a flush, thirty yards gain. Four of a kind (same value) on downs is twenty-five yards gain. Three of a kind (same value) gives side taking kick ten yards gain. 5 Two pair gives side taking kick five yards gain, (regardless of leader.) Forward pass gives, if successful, ten yards gain, but if lost, loses ball. Straight tackle advances 10 two yards, gain for side playing, on downs only. Off side tackle advances one yard, as soon as played, on downs only. (A foul tackle gains nothing). Foul tackle, played by defense, gives attacks five yards gain, 15 and if played by attacks, they lose the ball, only on downs. Tackle below, played by defense gives attacks five yards. Played by attacks, they lose the ball, on downs. Signals 7—11—7 and 11 in kick taken when 20 either led (on downs), (attacks always lead). Same suit, twenty yards, same color, opposite suits, fifteen yards gain, and of opposite colors, ten yards gain. 7—11 led as above by attacks, and kick goes to defense, with both the 7 and 11 in kick, they 25 lose the ball.
8. Suit must be followed, if suit card is held, except—(a) A tackle may be played at any time, on partner or opponent, and 30 counts as soon as played, on downs only. May play at kick off. No gain. (b) An “accident” may happen at any time, on downs to finish a straight. When the “accident” plays thus, or is in an otherwise 35 straight run, it is yet trump and assumes value of card for which it is substituted. (c) Trump or off suit card, as discard, only if no suit, called for is held.
8. If accident is led as trump, and later 40 a straight is formed, it still retains its trump value, except that it reverts to the corner value of the substituted card. Thus may the “accident” be nullified.
9. Ball lost back of the fifty yard line 45 of side in possession of ball loses the ball for next deal, and gives opponents two points in game.
10. Lonesome may be played as either high or low or counted so in runs. But does 50 not lose its high value as a kick taker.
11. No gain previously made avails for the ten yards needed “on downs” to hold the ball. Attacks must take two kicks on downs or lose the ball.
- 55 12. Corner values are not deducted save on kick off. Never on downs.
13. Kick for goal is made always after a touch down, and at no other time; then, if 60 in the draw the player who made the play that secured the touch down takes this kick, it is safe and scores 1. The “Kick for goal” is played by each drawing one card from the re-scrimmaged deck, leader is player whose card secured the touch down, and if he or 65 his partner takes that kick, count is safe.
14. Penalty and loss imposed by these rules that would result in a touch down is effective for only one-half distance to goal, even yards counted.
15. If touch down has been secured at ring 70 of bell, and kick for goal not yet played, this shall be played for the 1 count after bell rings.
16. Kickers played by defense at kick off have double value, thus their point value, 75 played by defense on kick off is twenty instead of ten. The other fouls count only their ten points on kick off. Kickers played on kick off by attacks carry no extra point value. Count ten only.
17. A card is in play only after it has touched the table, and cannot be changed, except it is the wrong card to play, when it should be made correct, but if wrongly played by an attack, they lose the ball, and if the play was by a defense, then they are penalized five yards. Any show of cards to a partner, if detected, loses ball for attacks or penalizes defense five yards. 80
18. 4—11—44 (the right guard, left half back and accident) in kick taken by one of the defense gives them only twenty yards gain, and if this reaches goal, then only one-half distance to gain in even yards, with possession of ball. 90
19. A card must have touched table in play before first sound of bell that ends each half, in order to count. 95
20. Coaching consisting only of calling partner’s or opponent’s attention to a proper 100 card to play at that time to make or hinder a point, is allowed, and for amateur players, recommended, but does not give any authority to tell or show cards any player may hold. 105
- Some examples on plays.*
- On kick off if trump accident leads, partner plays lonesome trump and opponents play respectively left and right half backs, the gain would be 44 plus 13 equals 57, and a trump 11 plus 12 (plays of defense) equals 23, then 57 minus 23 equals 34 yards gain, and peg or ball would rest at defense 34 yards line. 110
- On kick off if leader plays say right guard (4 trump), his partner plays left guard (3), and defense play accident and a kicker, it would be 44 plus 20 equals 64, minus (4 plus 3) or 57 yards, resulting in a touch back (3). 115
- On downs lonesome of off suit leads, left plays 2 of trump, partner 6 of suit and right 6 of same color, the tackle pushes the peg back two yards, and the kick goes to defense, but having tackled below, gives attacks five yards gain. Then if the defense secure the next kick, they get possession of ball without gain, and if they again take the third or last on downs, this would give five yards. 120
- 125
- 130

On downs lonesome led, left follows with tackle for one yard gain, partner plays suit 8 and right finishes kick with straight tackle for two yards, and this last play being 5 trump, take kick at tackle below, losing five yards, but the two pairs in kick would give them five yards, thus holding the opponents safe on downs, and if the defense get two kicks, the ball.

10 On downs, left half back (11) leads, trumps called for, left plays 7 trump, partner right end (8), and left tackle partner's 7 of trump; to save a flush, the kick goes to side in possession of ball on an 11 lead, thus 15 they gain twenty yards, less the value of defense tackle.

The game provides a great variety of plays and the combinations possible are almost endless. The game may be played 20 without the use of the board and the various gains marked on a blank piece of paper or on paper specially stamped for convenience.

It is of course to be understood that the 25 various decorations or suit symbols of the cards herein illustrated are intended to be simply a conventional distinguishing of the suits, and that I contemplate any desired configuration or finish in this respect.

Having thus described the invention, what I claim as new is:—

A game comprising a pack of cards, divided into a series of independent suits, a pair of said suits being provided with like matter distinguishing the same from the cards of the remaining suits, the cards of each suit having numerical values successively increasing by the single unit "one," and a plurality of controlling cards distinguishable from each other and from the cards of said suits, each controlling card being provided with a designation giving it a value depending thereon, while one card of the controlling cards has a value greater than all of the cards of the pack, but its value is destroyed by the playing, thereof in combination with certain of the cards of the suits and remaining controlling cards, and an additional card in each suit named for the full-back having its value determined by the play.

In testimony whereof I affix my signature in presence of two witnesses.

LEWELLEN A. ELY.
